UNITED STATES PATENT OFFICE.

SETH WHEELER, JR., OF ALBANY, NEW YORK.

ANCHOR-BOLT.

1,035,399.

Specification of Letters Patent. Patented Aug. 13, 1912.

Application filed February 8, 1910. Serial No. 542,735.

To all whom it may concern:

Be it known that I, SETH WHEELER, Jr., a citizen of the United States of America, and a resident of Albany, county of Albany, and State of New York, have invented certain new and useful Improvements in Anchor-Bolts, of which the following is a specification, reference being had to the accompanying drawings, forming a part thereof.

My invention relates to anchor bolts of the type employed for securing articles to walls, ceilings, and the like, and the object of my invention is to simplify the construction of anchor bolts of this description and decrease the cost of manufacture of the same while maintaining or increasing the efficiency thereof.

To these ends my invention consists in certain novel details of construction and combinations of parts such as will be fully pointed out hereinafter, and in order that my invention may be thoroughly understood, I will now proceed to describe an embodiment thereof, having reference to the accompanying drawings illustrating the same, and will then point out the novel features in a claim.

In the drawings: Figure 1 is a view in side elevation of an anchor bolt constructed in accordance with my invention showing the same in operative position in engagement with a wall. Fig. 2 is a detached face view of the same removed, and with the anchor element shown as moved to a position in line with the bolt. Fig. 3 is a rear view of the parts in the same position. Fig. 4 is an end view of the bolt with the anchor element shown as adjusted to a position at right angles to the shank. Fig. 5 is a view in side elevation of the bolt with the parts in the position in which they are shown in Fig. 4, the point of view being at right angles to that of Fig. 1. Fig. 6 is a view similar to Fig. 1 in side elevation of the bolt with the anchor portion shown in central longitudinal section. Fig. 7 is a detail detached view of an anchor of slightly modified form.

The bolt comprises a screw-threaded shank or bolt element 10, a nut 11 fitted thereto, and an anchor element 12 pivotally connected to the said nut. The anchor element 12 is preferably struck up from a flat sheet of metal, being made in trough-like form, with a base and side flanges, the said

base being provided with a central aperture 13 in line with the nut 11, and an elongated slot or opening 14 extending from this central aperture 13 to the end of the anchor upon one side thereof. Instead of cutting away the metal to form the slot or opening 14 the metal is preferably stamped up into arch-shaped form 20, whereby the same forms a bridge-like reinforcement yet allows the bolt to pass through the base to a position parallel therewith as is shown in the drawings. The opening is of a sufficient width for the shank 10 to pass freely therethrough, thereby permitting the anchor to swing from the position in which it is shown in Figs. 1, 4, 5, and 6 of the drawings in full lines, to the position in which it is shown in Figs. 1 and 6 in dotted lines, and in Figs. 2 and 3 in full lines. When in its former position the said anchor will present the rear flat surface 15 of its base to the rear of the wall 16 or other structure to which the anchor bolt is to be applied, thereby giving an extended bearing surface such as is particularly advantageous in many cases, particularly as where the bolt is applied to lath and plaster walls. It is understood, of course, that this bolt is applied in the usual manner in which these bolts are commonly applied,—that is to say, the anchor is folded down to a position in line with the nut, and is thereafter pushed longitudinally through a hole 17 in the wall, the anchor thereafter being swung over to a position at an angle to the shank and the shank then screwed down to place, whereby the anchor will be drawn up close against the rear face of the wall.

It is, of course, understood that the article intended to be secured in position upon the wall by the bolt has been omitted in the drawings.

The arch-shaped bridge piece 20 may, if desired, be dispensed with entirely as is shown in Fig. 7. Such construction is slightly cheaper to make but has less strength and for that and other reasons the form shown in the other figures is more advantageous.

The pivotal connection between the nut 11 and the anchor is conveniently formed by providing the nut with lateral trunnions 18 which are received in orifices 19 in the side walls of the trough-shaped anchor. This is very inexpensive in manufacture, as not only the anchor but also the nuts may be

stamped out of flat metal, rectangular extensions of the nut readily forming the necessary trunnions.

What I claim is:

- 5 The combination with a threaded bolt, and a nut thereon, of a trough-shaped anchor element comprising a base and flanges extending longitudinally of the element at right angles to the base, the said 10 nut being contained between said flanges and pivotally connected thereto, the said base at one side of the pivotal connection of the nut being struck up between the flanges to form

an arch-shaped reinforcement and provide a slot for receiving a bolt, whereby the bolt 15 may be swung from a position in line with and between the flanges of the anchor while extending an indefinite distance beyond the said nut, to a position at right angles to the base of said anchor, substantially as set 20 forth.

SETH WHEELER, JR.
